(57) **CLAIM**

The ornamental design for the pyramid solitaire puzzle, as shown and described.

DESCRIPTION

FIG. 1 is a front perspective view of the pyramid solitaire puzzle showing my new design with its play pieces in the starting position;

FIG. 2 is a front perspective view showing the design with play pieces repositioned after play has begun;

FIG. 3 is a top plan view of FIG. 1;

FIG. 4 is a front elevation view of FIG. 1;

FIG. 5 is a rear elevation view of FIG. 1;

FIG. 6 is a left end elevation view of FIG. 1; and,

FIG. 7 is a right end elevation view of FIG. 1.

The broken lines shown in FIGS. 1-3 are included for the purpose of representing surface indicia that forms no part of the claimed design.
